UNITED STATES PATENT OFFICE.

ALFRED JOPLING COOPER, OF LIVERPOOL, ENGLAND.

TURBINE.

No. 856,623.

Specification of Letters Patent.

Patented June 11, 1907.

Application filed April 21, 1906. Serial No. 313,045.

To all whom it may concern:

Be it known that I, ALFRED JOPLING COOPER, a subject of the King of England, residing at Liverpool, in the county of Lancaster, England, have invented new and useful Improvements in Turbines, of which the following is a specification.

This invention has reference to turbines driven by the force of steam or other motive fluid, due to the velocity and pressure thereof acting upon the surface of or on the parts of the motor or engine to be revolved; and it has primarily for its objects and effects, to provide a turbine which shall be simple in construction, powerful for a given size, and efficient at varying velocities, and in which the back pressures or negative pressures are obviated.

According to this invention, the turbine comprises a stationary cylinder, preferably of relatively large diameter and small width, and a rotatable part, called the rotor, within this cylinder mounted upon a shaft, and having blades or surfaces curved or inclined forward in the direction somewhat of the entrance of steam or motive fluid, and toward the center portion, upon which blades or surfaces the motive fluid is adapted to act and to flow in a curved or inclined direction to the blades, first toward the center, and then past the center, and outward from it toward the periphery, where it is discharged through a suitable exhaust passage. At the center, the inner ends of the two blades or surfaces will lie on opposite sides of the axis of the revolving part, so that the steam will pass from the one, after ceasing acting upon it, onto the other at the opposite side.

Examples of the turbine engine according to this invention are shown in the accompanying drawings.

In these drawings, Figures 1 and 2 are, respectively, outside end, and side elevations; and Figs. 3 and 4 are, respectively, transverse and vertical sections of a turbine motor according to this invention arranged as a non-reversing engine. Figs. 5 and 6 are transverse and vertical sections of the turbine motor hereunder, arranged and constructed as a reversible engine; and Fig. 7 is a plan in detail of the nozzle inlet port face. Fig. 8 is a diagrammatic section showing the turbine motor arranged in one form as a compound engine, that is, wherein the motor steam operates first in one cylinder, and then

in another, in series. Fig. 9 is a transverse section showing diagrammatically a modified form of reversible turbine hereunder.

Referring now to the drawings, and more particularly to Figs. 1 to 4, 1 is the outer stationary cylinder or casing; and 10 is the internal rotatable part or "rotor," which revolves within it, and, in the case shown, consists of a plurality of chambers, with vanes in them.

3 represent the nozzles through which the steam is introduced through the casing 1 into the rotor 10, of which there are three in the engine shown in these figures; and 4 is the steam chest from which the steam is distributed to the several nozzles, 3. These nozzles are so directed that the jets of steam issuing from them are more or less tangential to the periphery of the rotor 10.

The exhaust ports of the cylinder 1 are designated 5, and discharge into a common exhaust box 7 from which it is taken away, and exhausted either to a condenser, into the atmosphere, or to a second cylinder or engine.

12 are the blades of the rotor 10. They are of curved form, and the curvature from, say, about their centers in a forward direction toward the direction of entrance of steam on the one hand, and toward the center of the rotor on the other; and the steam is admitted to the rotor 10 through ports 13 in the periphery shell, that is, the cylindrical shell of the rotor, which is otherwise closed at its periphery, so that the motor steam strikes the sharp angle of one of the blades 12 at the point of entrance, first, and then the steam is gradually bent or curved round from this nearly tangential direction at the inlet, to a radial direction inward, toward the center of the rotor, at which point it—the steam—flows from the inner end of the one blade toward and onto the inner end of the other, and then in a reverse curved direction over this blade toward the periphery of the rotor, from whence it passes by the other of the ports 13 (which serve both as inlet and exhaust ports) out through the exhaust ports 5 of the cylinder 1.

The inlet nozzles or ports 3, and the exhaust ports 5 of the cylinder 1, are relatively so arranged in the case shown—which is an advantageous one—that when the port 13 of the rotor taking steam is opposite the nozzles 3, the other port 13 on the opposite side of the rotor, will not be open to the exhaust

ports 5. That is, the steam is admitted while the exhaust port is closed, but the exhaust is opened very soon after the inlet takes place.

5 In the case shown, the rotor 10 consists of three separate chambers in parallel, built or constructed in any suitable or convenient way; the outer chambers being separated from the center one by partitions 15, and closed at their ends by walls or plates 16.

The shaft 17 of the engine or turbine is preferably fixed by flanges onto the outside of the end plates 16, as shown, or in any suitable way, so as not to interfere with the flow of the steam in passing from the first vane 12 onto the other, in traversing the center portion of the rotor.

15 The vanes of the different chambers of the rotor are set at different points around the center, so as to supply the steam to it from the several nozzles at different points in its circumference and revolution, and so to distribute as equally as possible the turning or rotating pressure and effect of the steam on the rotor as a whole.

20 In some cases, the ports 13 have extending from them in a direction away, or in front of the blades 12, a narrow extension portion or slot 14, by which a diminished quantity of steam would be supplied to the rotor, after the main or larger portion 13 of the port has passed the nozzles. These ports are shown clearly in Figs. 3 and 4.

25 In passing through the rotor 10, the force of the steam is fully absorbed by first having to act upon one of the blades 12, in one direction of curvature, and then by acting upon the second blade of the reverse curvature, and traversing it. At the points at which it is discharged through the ports 13 or 14 into the cylinder exhaust ports 5, it will be arranged that its propulsive power is practically utilized; but if, as in cases where high pressure are used, or cylinders are small, the 30 force of the steam may not be expended, then it may be utilized to propel other engines as in the case shown in Fig. 8, or otherwise, as may be desired.

35 Referring to the type of reversible turbine shown in Figs. 5 and 6, in this case there are two sets of blades 12 on each side of the center of the rotor, the outer ends of which are adjacent to each other, and the inner ends of the one set, for driving in one direction, and those for driving in the opposite direction, meet, and are joined up, as shown. In this case, two sets of steam inlet ports 3 are used, and the steam is distributed to one or other of the sets of ports by a valve 18, which is moved over the port face 20 within the chest 4. When the valve is at one end of this chest, one set of ports or nozzles are open, and the other closed, while when at the other, the opposite set are open and the other shut; while, when it is in the center,

both are closed. This valve 18 practically consists of a simple plate, to which an operating rod 19 is connected.

The "astern" and "ahead" ports or nozzles are arranged side by side in connection with each portion of the rotor 10 with which they respectively act, so that the extended portion 14 of the ports 13 for going, say "ahead", will not be acted upon by steam used for driving "astern", and vice versa. This relative arrangement is shown clearly by the drawings. In this case, the extended portions 14 of the ports 13 are each in the form of a groove, in the barrel or shell of the rotor, it being deepest and of the greatest area where it runs into the port 13, and shallowing off toward its extremity or outer end.

40 In this reversible engine shown in Figs. 5 to 7, two sets of exhaust ports 5 are employed in the casing 1; one in connection with the set of blades 12 for driving the engine in one way; and the other set of blades, as will be understood; the relative arrangement between the inlet nozzles or ports 3, and the discharge ports 5 of the cylinder case 1, being similar to that set out with reference to Figs. 1 to 4, for the purpose and objects therein explained.

45 Referring now to the compound arrangement of turbine motor shown in Fig. 8, which is a tandem arrangement, there is used in connection with the primary cylinder 1 and rotor 10, a second and larger cylinder 2 and rotor 11; the second cylinder and rotor being identical in form with the primary one; and the exhaust passage or port 5 being so arranged that the steam discharged from 1 into this port, is directed by it in the form of jets in a more or less tangential direction to the rotor 11, as shown in Fig. 8. The steam in passing through this second rotor 11 acts on the blades therein, similarly as in the rotor 10, and exhausts through the exhaust ports 6 thereof, similarly as the steam exhausts from the first rotor 10 into the port or passage 5.

50 With regard to the modified form of reversing engine shown in Fig. 9, supplementary steam inlet ports or nozzles 8 are used in it, the main steam inlet nozzles or ports 3 being provided and arranged in the manner already described. The inlet port or ports 8 is or are so arranged that the jets from them flow and impinge in the angular space between the backs of the blades 12 and the inside surface of the shell of the rotor, and act by direct impact pressure into these spaces, which may be filled with metal, more or less, in the manner indicated by the shaded part.

55 An inlet port 9 for the steam is provided in this barrel or shell of the rotor 10 behind these portions of the blade which are acted upon by the jets supplied through the nozzles 8; and the steam after acting or impinging on the rotor, is discharged through the

exhaust port 5 in the cylinder 1. Otherwise, the motor is precisely similar to that shown in Figs. 1 to 4.

It is to be noted that these ports or nozzles 8 for the astern or reverse driving of the engine in Fig. 9 will preferably be of much greater area than those for driving ahead.

In the turbine herein described, it will be noted that the steam is not continuously flowing into and acting on portions of the rotor 10, but is admitted to and acting on the propelling portions of same, in puffs or for short sections of its revolution; and then is cut off, and allowed to pass through the rotor; and act upon the blades therein, and produce the rotative or propelling effect in its flow over them, and through the rotor, as herein described. And the duration and extent of the supply of motive fluid is governed by the shell of the rotor itself; that is, the steam is admitted and cut off automatically by the periphery of the rotor, which thus acts as a true supply and cut off valve to the supply of fluid.

25 What is claimed is:—

1. A turbine comprising a casing having inlet and exhaust ports therein, a rotor in said casing, said rotor being in the form of a casing and having inlet and exhaust ports therein, a curved blade connected to the periphery of the rotor and extending inwardly to the diameter of the rotor and to one side of the center thereof, and a second blade connected to the periphery of the rotor on the side opposite to that which the first men-

tioned blade is secured, said second blade being of opposite curve to the first blade and extending inwardly to the diameter of the rotor and to one side of the center thereof.

2. The herein described improved turbine, 40 namely, a turbine having within it a rotary portion comprising a cylinder with ports in its periphery for the inlet and outlet of the steam to and from it, on opposite sides, and with two sets of curved blades of opposite 45 curvature, extending between the periphery, at each side of said ports, and the center, and two sets of motor fluid inlet nozzles in opposite directions; substantially as and for the purposes set forth.

3. A turbine comprising a casing, a rotor 50 therein having ports 13 in its periphery and elongated openings 14 extending circumferentially from said ports 13.

4. A turbine comprising a rotor consisting 55 of a cylindrical shell having parallel partitions therein forming a plurality of chambers, each of said chambers having inlet and outlet ports therein and curved plates in each chamber extending from the periphery to a 60 point near the center, said plates in the different chambers being spaced apart circumferentially, one in advance of the other.

In testimony whereof I have signed my name to this specification in the presence of 65 two subscribing witnesses.
